UNITED STATES PATENT OFFICE

132,688

DESIGN FOR A PIN OR SIMILAR ARTICLE

Jessie N. Powell, Chevy Chase, Md.

Application January 21, 1942, Serial No. 105,349

Term of patent 3½ years

To all whom it may concern:

Be it known that I, Jessie N. Powell, a citizen of the United States, residing at Chevy Chase, Maryland, have invented a new, original, and ornamental Design for a Pin or Similar Article, of which the following is a specification, reference being had to the accompanying drawing, forming a part thereof.

I claim:

The ornamental design for a pin or similar article, substantially as shown.

JESSIE N. POWELL.
